CLAIM

The ornamental design for a sensor module, as shown and described.

DESCRIPTION

FIG. 1 is a front, top, right side perspective view of a sensor module, showing the new design;

FIG. 2 is a rear, top, right side perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof, a left side view being a mirror image thereof;

FIG. 8 is a cross-sectional view thereof taken at line 8-8 in FIG. 3; and,

FIG. 9 is a cross-sectional view thereof taken at line 9-9 in FIG. 3.

Evenly broken lines depict portions of the sensor module which form no part of the claimed design.

1 Claim, 9 Drawing Sheets
